UNITED STATES PATENT OFFICE.

WILLIAM SIEBERT, OF CHICAGO, ILLINOIS.

PANEL STRUCTURE.

1,223,431.

Specification of Letters Patent. Patented Apr. 24, 1917.

Application filed April 5, 1915. Serial No. 19,151.

To all whom it may concern:

Be it known that I, WILLIAM SIEBERT, citizen of the United States, residing at Chicago, in the county of Cook and State of Illinois, have invented a certain new and useful Improvement in Panel Structures, of which the following is a full, clear, concise, and exact description, reference being had to the accompanying drawings, forming 10 a part of this specification.

My invention relates to panel structures and is of particular utility when embraced in the formation of counters. One of the features of my invention includes adjacent 15 pilasters which carry clamping devices at their rear sides for forwardly pressing a panel into engagement with these pilasters.

The material of which the panel is formed is desirably translucent or clouded glass 20 and is therefore fragile. I desirably mount the panel in a box, which box is therefore directly engaged by the panel holding clamping means, the box itself having some suitable panel holding agency such as a lining 25 of putty upon its upright bottom. The counter is provided with rails at its top and bottom, the forward rails engaging the glass panels and coöperating with the putty to hold them in place.

30 The invention has other features and characteristics and will be fully explained by reference to the accompanying drawings showing the preferred embodiment thereof and in which Figure 1 is a cross sectional view of a counter embracing the invention; Fig. 2 is a front view taken on line 2 2 of Fig. 1; Fig. 3 is a view on line 3 3 of Fig. 1; Fig. 4 is a view on line 4 4 of Fig. 3; Fig. 5 is a view on line 5 5 of Fig. 2; Fig. 40 6 is a plan view of the counter with the top or counter shelf removed; Fig. 7 is a view on line 7 7 of Fig. 6; Fig. 8 is a view on a larger scale of a part of the structure as 45 illustrated in Fig. 1; and Fig. 9 is a rear view of a part of the pilaster portion shown in Fig. 8.

Like parts are indicated by similar characters of reference throughout the different figures.

50 The counter or table top 1, preferably in the form of translucent or clouded plate glass, is supported upon the upper ends of the pilasters 2 (preferably in the form of metal castings), the rear pilasters being desirably arranged close to the inner or rear edge of the counter top while the outer pilas- 55 ters are removed a considerable distance from the front edge of the counter top. Each forward pilaster therefore desirably carries a forwardly projecting bracket 3 60 (preferably in the form of a metal casting) for engaging and supporting the front overhanging portion of the counter top 1. A metallic molding 4 is carried upon the bottom side of the counter top and has a ledge 65 5 which is received in recesses in the tops of brackets 3 so that the ledge 5 and the tops of the brackets 3 are flush so as to engage the bottom of the counter top. The ledge 5 is screwed to the forward end of the bracket 70 3 instead of to the counter top. Each forward pilaster is desirably accompanied by a rear pilaster which is in the same plane therewith, such two pilasters intervening between adjacent counter sections and taking 75 part in defining the same. Each counter section includes forward and rear top rails 6 engaging the bottom of the counter top 1, the rails of a section being joined by a strut 7 screwed thereto. Adjacent aligned rails 6 80 of adjacent counter sections are joined by struts 8 that are screwed thereto and which are located where the pilasters are disposed. The pilasters are provided, at their mid portions, with insetting lugs 9, the forward and 85 rear pilasters of each pair being joined by a strut 10 screwed to the lugs 9 thereof. The lower portions of the front and rear pilasters of each pair are united by a strut 11 90 screwed thereto. Each pilaster may terminate in a foot 12 at its lower end. Each foot carries a leveling bolt 13 accessible for operation through an opening 14 whereby the counter may be leveled. The lower part of each pilaster has a lower insetting lug 15 95 and two upper insetting lugs 16 each at a side of the pilaster. Each counter section includes forward and rear bottom rails 17 which rest upon the lugs 15 and are themselves beneath the lugs 16 whereby these bottom rails are positioned with respect to the pilasters. The rails 17 are of angular formation, being also preferably of metal, the horizontal branches of these rails resting 100 upon the tops of the feet 12. The front 105 panel of each counter section includes a wall 18 which is desirably in the form of a rectangular body of translucent or clouded plate glass which is disposed within a sheet metal pan 19 having outsetting sides that 110 closely approach the edges of the glass panel 18, the upright bottom of the pan that is be-

hind the glass being desirably faced with putty 20 to hold the glass and pan together. The bottom rails 17 have insetting horizontal ledges 17¹, the bottom sides of the boxes 19 resting upon the ledges 17¹ of the forward rail 17 instead of directly upon the feet 12 whereby the bottom edges of the pans have supporting engagement throughout and are prevented from sagging. The forward rail 17 is provided with an insetting ledge 21 for engaging the front face of the glass panel near the lower part thereof, the upper front rail 6 of each panel desirably also similarly engaging the glass, the layer of putty 20 thus being coöperated with to prevent separation of the glass and the glass holding pan 19. Each forward pilaster 2 carries two insetting threaded bolts 22, one located near the top of the pilaster and the other near the bottom thereof. Each bolt has a wing nut 23 adapted to be brought into engagement with a clamping plate 24 that may be clamped against the rear of the box 19 of adjacent panels, these plates being quite loose upon the bolts readily to adapt them to adjacent panels. The pilasters are provided with lugs 2¹ whose inner faces define with the side faces of the pilasters angular pockets for receiving the rails 6 and locating them in position whereby the struts 8 do not have to be relied upon altogether for this purpose.

The spaces between the rear pilasters 2 are generally not filled in whereby ready access may be afforded to the spacing below the counter top and back of the front panels. Where the spacing beneath the counter top is to be occupied by goods, an intermediate shelf 24¹ is mounted upon the shelf supporting rails 25 that extend lengthwise of the counter and which supporting rails are in turn supported by the insetting lugs 9 to which they are screwed. The rails 25 are desirably in the form of angle irons disposed to have one wall of each horizontal to support the shelving 24¹ and the other wall thereof vertical and placed outwardly to rest against the structure of the pilasters in the case of the rear rail 25 and against the upright bottoms of the glass holding pans 19 in the case of the forward rail 25. These

vertical walls of the angle irons 25 are cut away (as indicated most clearly in Fig. 3) to accommodate the insetting lugs 9. The bottom of the counter structure is also desirably provided with shelving indicated at 26 supported by the ledges 17¹ and which may also be of the same material as the elements 1 and 24¹. When the space beneath the counter top is thus arranged for storage the pans 19 not only serve to hold the panes of glass in position but also act as cushions to protect the glass from the impact of objects carelessly thrown upon the inner shelving.

65

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A panel structure including a number 75 of spaced apart pilasters defining a plurality of adjacent panel spaces, said pilasters being provided near their bottom ends with lower and upper lugs; and a bottom rail resting upon the lower lugs and disposed beneath the upper lugs.

2. A panel structure including spaced apart pilasters defining adjacent panel spaces; inwardly extending threaded bolts carried by the pilasters; clamping plates 85 upon the bolts; clamping nuts upon the bolts adapted to be moved against the clamping plates; and panels in adjacent panel spaces held in place between rear portions of the pilasters and the clamping plates by the 90 clamping nuts, said clamping plates being loosely disposed upon the bolts to enable the clamping plates readily to be adapted to adjacent panels with which each clamping plate may be engaged.

In witness whereof, I hereunto subscribe my name this 29th day of March A. D., 1915.

WILLIAM SIEBERT.
